(57) **CLAIM**

The ornamental design for a pillow, as shown and described.

DESCRIPTION

FIG. 1 is a front, top, and right-side perspective view of a pillow according to a first embodiment of the present invention;

FIG. 2 is a front elevational view of the pillow shown in FIG. 1;

FIG. 3 is a rear elevational view of the pillow shown in FIG. 1;

FIG. 4 is a right-side elevational view of the pillow shown in FIG. 1;

FIG. 5 is a left-side elevational view of the pillow shown in FIG. 1;

FIG. 6 is a bottom plan view of the pillow shown in FIG. 1;

FIG. 7 is a top plan view of the pillow shown in FIG. 1;

FIG. 8 is a front, top, and right-side perspective view of a pillow according to a second embodiment of the present invention;

FIG. 9 is a front elevational view of the pillow shown in FIG. 8;

FIG. 10 is a rear elevational view of the pillow shown in FIG. 8;

FIG. 11 is a right-side elevational view of the pillow shown in FIG. 8;

FIG. 12 is a left-side elevational view of the pillow shown in FIG. 8;

FIG. 13 is a bottom plan view of the pillow shown in FIG. 8;

FIG. 14 is a top plan view of the pillow shown in FIG. 8;

FIG. 15 is a front, top, and right-side perspective view of a pillow according to a third embodiment of the present invention;

FIG. 16 is a front elevational view of the pillow shown in FIG. 15;

FIG. 17 is a rear elevational view of the pillow shown in FIG. 15;

FIG. 18 is a right-side elevational view of the pillow shown in FIG. 15;

FIG. 19 is a left-side elevational view of the pillow shown in FIG. 15;

(Continued)

FIG. 20 is a bottom plan view of the pillow shown in FIG. 15; and,

FIG. 21 is a top plan view of the pillow shown in FIG. 15. The surface shading, if any, illustrated in the drawings is provided merely to highlight the contour of the design; it is not intended to be illustrative of texture or gloss.

1 Claim, 21 Drawing Sheets
